[57] **CLAIM**

The ornamental design for a clock, substantially as shown and described.

DESCRIPTION

FIG. 1 is a front elevational view of a clock in a closed state showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a cross-sectional view thereof taken generally along the line 7—7 of FIG. 1 with the inner contents thereof omitted for clarity;

FIG. 8 is a top plan view thereof showing the clock in an open state;

FIG. 9 is a bottom plan view thereof in an open state;

FIG. 10 is a rear elevational view thereof in an open state; and

FIG. 11 is a right side elevational view thereof in an open state, the left side view being a mirror image thereto.
